UNITED STATES PATENT OFFICE.

FRANK H. BACHELDER, OF ORANGE, MASSACHUSETTS.

HEMSTITCHING ATTACHMENT FOR SEWING-MACHINES.

1,265,585.

Specification of Letters Patent. Patented May 7, 1918.

Application filed December 6, 1917. Serial No. 205,730.

To all whom it may concern:

Be it known that I, FRANK H. BACHELDER, a citizen of the United States, residing at Orange, in the county of Franklin and State 5 of Massachusetts, have invented certain new and useful Improvements in Hemstitching Attachments for Sewing-Machines, of which the following is a specification, reference being had therein to the accompanying drawing.

This invention relates to improvements in hemstitching attachments for sewing-machines, and one of its objects is to construct the attachment so that it can be applied to 15 the ordinary sewing-machine presser foot-holder by the means used for applying other attachments thereto and without extra screws, slides, clamps or tools to attach it.

Another object of the present invention 20 is to construct the attachment with an adjustable gage for hemstitching at various distances from the edge of the goods, and which gage serves to hold the edges in perfect alinement during the hemstitching 25 thereof.

A further object is to so construct the attachment that it can be used on either the vibrating or rotary shuttle-type of sewing machine without any change in the 30 machine.

Another object is to provide a hemstitching attachment with means for varying the width of the hemstitching (making it narrow or wide) by a tension device combined 35 with the hemstitcher and applicable to the ordinary sewing machine so that the turning of a screw will regulate the width of the hemstitching.

A further object of the present invention 40 is to provide the hemstitching attachment with a tension device independent of the tension on the sewing machine, thereby avoiding the necessity of changing the sewing machine tension and the chance thereby 45 of getting the sewing machine out of proper tension adjustment.

In the accompanying drawings

Figure 1 is a perspective view of a sewing machine showing the improved hemstitching attachment and tension therefor applied 50 to the machine.

Fig. 2 is an enlarged top plan view of

the hemstitching attachment, omitting the tension device.

Fig. 3 is an enlarged sectional view on the 55 line 3—3 of Fig. 2.

Fig. 4 is a sectional view on the line 4—4 of Fig. 2.

Fig. 5 is a perspective view showing a 60 partially completed hemstitching.

Fig. 6 shows a completed hemstitching.

Referring now to the drawings in which like reference characters designate the same parts, 1 is the arm of a sewing machine, 2 the bed; 3 the head and 4 the presser foot- 65 holder.

The improved attachment comprises a body-portion made up of two arms 5 and 6, separated by a slightly inclined slot 7. The outer or front end of the arm 5 is provided 70 with an upwardly and laterally projecting bifurcated attachment arm 8, by which the device is attachable to the lower end of the presser foot rod 4 with the usual attaching means 9, so that no additional means of 75 attachment is necessary from that found on the ordinary machine.

A needle opening 10 is provided in the arm 6, near the slot 7, and this eye opens 80 into the slot 7 by a slot 11.

An adjustable gage plate 12 is carried by the rear portion of the arm 6, and this gage-plate is provided with a longitudinal slot 13. A guiding pin 14 passes through the slot 13 and into the arm 6, or rear portion 85 15 of the attachment, and a thumb-clamping screw 16 passes through the same slot 13 in rear of the pin 14 and into the portion 15 of the attachment by means of which the gage-plate is clamped in its de- 90 sired adjustment, the plate being readily moved by an up-turned end 17.

The outer end of the gage-plate 12, is provided with two fabric guiding tongues or arms, the upper arm 18 being above the 95 arm 6 of the attachment, and the lower one 19 has its lower surface approximately in the plane of the bottom of the arm 6.

Figs. 2, 3 and 4, are views about one and one-half times larger than the full-sized 100 devices.

Combined and operating with this attachment is a tension device, consisting of an arm 20 having an eye 21 at its rear end to

receive the projecting end of the rod 22 on which the spool of thread 23 is placed. This arm carries a tension device 24 of the usual disk-type, and the thread 23 passes between these disks and through the slots 26 to the usual threading members of the sewing machine, so well understood that further reference thereto is not necessary, and down to the needle 27.

10 In operation the piece of cloth that is to form the hem, and hereinafter referred to as the upper piece of cloth 28, is passed through the slot 7, as shown in Fig. 3. This piece of cloth should ordinarily be a trifle more than twice as wide as the finished hem is desired to be. The under piece of cloth 29 is of any desired width, such as a skirt or other garment. The inner edge of the narrow piece 28, which passes through the slot 7, also passes under the arm 18, as shown in Fig. 4, and in this way the gage-plate regulates the distance between the edge of the cloth and where the needle passes through it, and the lower cloth 29 passes over the arm 19 with its inner edge in a vertical line above the inner edge of the upper cloth. In this way the two edges of the cloth are held in vertical alinement at the desired distance from the point of sewing, and these arms enable the hemstitching to be accurate and straight. In this position the arm 6 separates the upper and lower pieces of cloth, as clearly shown in Fig. 3, and holds them apart during the stitching operation.

After the goods are sewed together in separated relation, the edges are turned back, as shown in Fig. 5, at 30 and 31, and the upper or narrow strip is folded over 40 and sewed down close to the hemstitching, as shown at 32, and the remaining edge is cut close and folded in and sewed down close to the other side of the hemstitching.

The width of the hemstitching 33 is controlled by the tension device. That is to say, a tight tension will more closely draw the pieces together and make a narrow hemstitching, and a loose tension will have the reverse effect and make a corresponding wider hemstitching, when the two pieces are doubled in the position shown in Fig. 5, and pulled apart to be sewed, as described to finish the hemstitching.

A sewing machine tension 34 of any desired form, is shown on the arm 1 of the machine in Fig. 1. The operation and function of this ordinary tension is well understood by those skilled in the art.

Having thus described my invention, what I claim and desire to secure by Letters Patent is:

1. A hemstitching attachment comprising a body-portion having parallel arms separated by a slot, the free end of one of the arms having an outwardly projecting

arm with a vertical open-ended slot forming two horizontal arms in the same horizontal plane adapting the said arm for attachment to the bottom of the lower end of the presser-foot holder.

2. A hemstitching attachment comprising a body-portion, having parallel arms separated by a slot, the free end of one of the arms having an outwardly projecting bifurcated member for attachment to the 75 presser-foot holder of a sewing machine, a sliding gage coöperating with the other arm and having members for guiding the upper and lower pieces of cloth, for the purpose described.

3. A hemstitching attachment comprising a body-portion having parallel arms separated by a slot, the free end of one of the arms having an outwardly extending bifurcated member for attachment to the sewing machine presser-foot holder, and a gage-plate 85 slidable over the other arm, the outer end of the gage plate having arms in different horizontal planes, for the purpose described, and means for holding the gage-plate in adjustable positions.

4. A hemstitching attachment comprising a body-portion having parallel arms separated by a slot, the free end of one of the arms having an outwardly extending bifurcated member for attachment to the presser-foot holder of a sewing machine, an adjustable gage-plate coöperating with the other arm, the outer end of the gage-plate having parallel arms, one in a horizontal plane 100 above the second said attachment arm, and the other gage-plate arm below the upper surface of the second said attachment arm, for the purpose described, and means for holding the gage-plate in its position.

5. A hemstitching attachment comprising parallel arms, separated by a slot, the free end of one arm having an upwardly and outwardly extending bifurcated member for attachment to the sewing machine presser-foot holder, the free end of the other arm having a needle opening in communication with said slot, a gage-plate movable longitudinally on the upper face of the second said attachment arm, said gage-plate having a longitudinal slot, clamping means passing through the slot and into the attachment, the outer end of the gage-plate having an arm extending above the upper face of the attachment, and a second arm 110 in a plane below said upper face of the attachment, the parts combined for the purpose described.

6. A hemstitching attachment comprising a body-portion having parallel arms separated by a slot, one of said arms carrying a member for attachment to the sewing machine presser-foot holder, and the other arm provided with a gage for adjustably guiding the goods being hemstitched.

7. A hemstitching attachment comprising a body-portion having parallel arms separated by a slot, one of said arms having at its free end a member for attachment to the sewing machine presser-foot holder, the other arm having a needle opening in communication with the slot and located in a line with the said attachment member, and a sliding adjustable gage on the arm which is provided with a needle opening, the gage

adapted to guide the edges of the goods being hemstitched at adjustable distances from the needle opening.

In testimony whereof I hereunto affix my signature in the presence of two witnesses.
